[57] CLAIM

The ornamental design for a carafe, as shown and described.

DESCRIPTION

FIG. 1 is a perspective view of my new design of a carafe; FIG. 2 is a front elevational view of my new design of the carafe;

FIG. 3 is a rear elevational view of my new design of the carafe;

FIG. 4 is a right side elevational view of my new design of the carafe, the left side elevational view of my new design of the carafe being a mirror image of the right elevational view of my new design of the carafe;

FIG. 5 is a top plan view of my new design of the carafe; and,

FIG. 6 is a bottom plan view of my new design of the carafe.
